UNITED STATES PATENT OFFICE.

CHARLES D. MORRIS, OF NORFOLK, VIRGINIA.

OPERATING DEVICE FOR TRAIN-PIPE COCKS.

1,134,546.

Specification of Letters Patent.

Patented Apr. 6, 1915.

Application filed April 15, 1914. Serial No. 831,983.

To all whom it may concern:

Be it known that I, CHARLES D. MORRIS, a citizen of the United States of America, and resident of Norfolk, county of Norfolk, and State of Virginia, have invented certain new and useful Improvements in Operating Devices for Train-Pipe Cocks, of which the following is a specification.

This invention relates to certain new and useful improvements in operating devices for train-pipe cocks of that class in which means are provided for opening and closing the cocks from the side of the car without going between cars.

The present invention has for its objects among others to provide simple and efficient means whereby the cocks may be operated from both sides of the car, and actuation of the means upon either side of the car serves to control the cock governing both the train-line pipe and the whistle or signal line pipe.

It has for a further object to provide means whereby two cocks may be operated by the same handle and avoiding all mistakes, although the parts are disposed beneath the car body out of sight.

In case of injury to the exhaust cock, all it is necessary to do is to remove the cap nut from the valve and repair it or replace it with a new one.

I employ also an improved form of handle, in one piece or with the parts all rigid so as to avoid lost motion.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which—

Figure 1 is an under plan view of a portion of a car with my improvements applied. Fig. 2 is a vertical transverse section 45 through the same. Fig. 3 is a horizontal section through the cock with a portion broken away. Fig. 4 is a perspective view of the handle for the whistle cock. Fig. 5 is a similar view of the handle for the cock of 50 the train-line pipe.

Like numerals of reference indicate like parts throughout the different views.

Referring to the drawing, 1 designates the side sills of a car as viewed from the under side looking up. It is to be understood that the parts not herein particularly referred to,

as well as the other parts of the car, the train-pipes, etc., may be of any well-known or approved forms of construction. In the space 3 between the sills are located the valves, 4 being the whistle or signal line pipe and 5 the train-line pipe, these being equipped in the usual way and operating as is common in this class of devices, except as will now be particularly described.

The valves or cocks in the pipes may be of any desired form, but are preferably of the construction shown in Fig. 3, in which 6 is the casting or casing in which the plug valve 7 is rotatably mounted, the valve plug 65 being provided with a port 8, a rectangular or polygonal stem 9 for the attachment of the handle, and with an opening 10 for the reception of a pin or other means for fastening the handle in position. It is provided with the oppositely disposed threaded nipples 11 and 12 for the connection of the pipes and with a hose release port 13. The cap nut 14 is threaded into the casing and has a chamber 15 in which is arranged a 70 spring 16 for holding the plug in place. The port 13 communicates with this chamber 15, while 17 is an exhaust cock for controlling the port 13.

The cocks are operated in the following 85 manner: 18 is the handle for the cock of the signal pipe 4. It has a rectangular socket 19 to engage the rectangular portion 9 of the stem and a rigid operating arm 20 with an opening 21 for the attachment of 90 the connection 22 which serves to connect the same with the opening 23 in the arm 24 on the stem 25 which has a rectangular socket 26 for the reception of and attachment to the rectangular portion 9 of the 95 cock of the train-line pipe 5. This stem has rigid therewith the two arms 27 and 28 extending in opposite directions and provided with openings 29, with one of which connects the operating lever 30 and with the 100 other is connected the operating lever 31. These levers are supported and guided in suitable brackets or the like 32 depending from the under side of the car frame. The arm 24 is provided with a stop 33 adapted to engage a stop 34 on the valve casing 6, shown plainly in Fig. 3, to limit the movement of the handle. The stem 18 is likewise provided with a stop 37 adapted to engage a stop 34 on the valve casing.

It is deemed important that the arm 24 extend rigidly from the stem 25 and at right

angles to the arms 27 and 28 and that it be centered on the said stem and the pivot of the arms 27 and 28 so that the connection 22 may extend parallel with the train pipes 5 and that this connection be attached directly to the free end of the arm 24 and the operating arm 20. This provides compact arrangement, gives me a long connection between the arms 20 and 24 and the valves are 10 operated immediately upon actuation of the operating levers 30 or 31. It minimizes the parts, cheapens the construction and lessens the liability of damage or derangement.

With the parts constructed and arranged 15 substantially as hereinbefore described, the operation will be readily understood from the foregoing description, especially when taken in connection with the annexed drawings. When occasion may require, the ex- 20 haust cock 17 is turned so as to exhaust the air through the port 13 and chamber 15.

It will be noted that both cocks are simultaneously actuated by the manipulation of the levers and that both cocks will be simultaneously actuated by movement of either lever, upon either side of the car. The cocks and their operating means are all located beneath the car where they are all out of sight and free from all liability of injury, yet 30 easily operated and reliable and positive in their operation.

Modifications in details may be resorted to without departing from the spirit of the invention or sacrificing any of its advantages.

35 What is claimed as new is:—

1. Means for simultaneously actuating the cocks of train-line and signal pipes, comprising stems attached to said cocks, oppositely disposed arms connected with one of 40 said stems, an independent arm rigid with said stem extending at substantially right angles to the first-named arms, actuating means for said arms projecting to either side of the car, an arm rigid with the stem 45 of the other valve, and a connection between

the last-named arm and said right-angled arm and extending substantially parallel with said train-line and signal pipes.

2. Means for simultaneously actuating the cocks of train-line and signal pipes, comprising stems attached to said cocks, oppositely disposed arms connected with one of said stems, an independent arm rigid with said stem extending at substantially right angles to the first-named arms, actuating means for said arms projecting to either side of the car, an arm rigid with the stem of the other valve, a connection between the last-named arm and said right-angled arm and extending substantially parallel with 55 said train-line and signal pipes, a stop on said right-angled arm and coöperating means on the valve casing to limit the movement of the operating lever.

3. Means for simultaneously actuating the cocks of train-line and signal pipes, comprising stems attached to said cocks, oppositely disposed arms connected with one of said stems, an independent arm rigid with said stem extending at substantially right angles to the first-named arms, actuating means for said arms projecting to either side of the car, an arm rigid with the stem of the other valve, a connection between the last-named arm and said right-angled arm and extending substantially parallel with 70 said train-line and signal pipes, an angular integral vertically disposed stop on said right-angled arm and coöperating means on the valve casing to limit the movement of 75 the operating lever, and an integral angular vertically disposed stop on the other stem coöperating with its casing.

Signed by me at Norfolk, Virginia, this 8th day of April 1914.

CHARLES D. MORRIS.
